ELECTRIC LOGGING WITH OIL BASE
DRILLING FLUIDS

Roland F. Krueger, Redondo Beach, Calif., assignor to Union Oil Company of California, Los Angeles, Calif., a corporation of California

Application December 12, 1949, Serial No. 132,457

10 Claims. (Cl. 175—182)

1

This invention relates generally to electric logging with oil base drilling fluids or muds, and more particularly relates to a method for rendering certain oil base drilling fluids conductive during electric logging operations.

The measurement of the resistivity of the different earth formations traversed by drill holes has become standard practice in oil well drilling during the last twenty years. The techniques in use require that a direct contact be made with the mud filling the bore hole by means of electrodes which are electrically connected to the insulated leads of the supporting cable. A current of constant intensity is generally made to flow in the surrounding medium through one or two of these electrodes, called power electrodes. By ohmic effect potential differences are produced in the surrounding formation, the magnitude of the potential difference being proportional to the average resistivity of the formation. These potential differences are measured by one or more measuring electrodes and the results are recorded continuously at the earth's surface to give the resistivity log.

In certain cases good contact between the electrodes and the surrounding formation under scrutiny cannot be obtained, such as where the well bore has been drilled with a normally non-conductive oil base drilling fluid which partially penetrates and seals off the earth formation surrounding the well bore. The oil saturated lining of the bore hole acts as an electrical insulator, and electrical contact can only be established, if at all, by the use of scratchers or other devices which must successfully penetrate the oil film and contact the bare earth formation.

A number of other methods such as electromagnetic logging, induction logging and the like have been developed to circumvent the requirement of directly contacting the earth formation and the problems associated therewith. These innovations yield data which must be related by empirical methods to the customary electric log and are disadvantageous for this reason.

The disadvantage of complications in the electric logging does not preclude the use of oil base drilling fluids since their use offers certain advantages which considerably outweigh this disadvantage. Any fluid loss from an oil base drilling fluid is oil and as such is entirely compatible with the oil-bearing formation, heaving shales and the like. Water base muds on the other hand lose water which often causes water blocking of oil-bearing formations, wetting and swelling of formations such as heaving shales and the like.

2

The present invention comprises the use of an alternating electrical potential gradient in conjunction with certain types of oil base drilling fluids whereby such fluids are rendered electrically conductive so that the well bore fluid, as well as the envelope of oil base mud saturated earth formation cease to be electrical insulators but become electrically conductive.

It is an object of this invention to improve the electric logging of uncased bore holes which have been drilled with, and/or filled with, a normally non-conductive oil base drilling fluid.

It is another object of this invention to render normally non-conductive oil base drilling fluids electrically conductive.

It is another object of this invention to provide a method and apparatus for establishing an alternating electrical potential gradient throughout a section of a non-conductive oil base drilling fluid under such conditions that the drilling fluid is made to conduct electrical energy.

It is another object of this invention to cause a dielectric breakdown of oil base drilling fluids containing both water and metallic soaps whereby such drilling fluids become electrically conductive.

Briefly this invention includes the step of establishing an alternating electrical potential gradient throughout the region of an oil base drilling fluid whereby the normally non-conductive fluid is rendered conductive.

Only certain oil base drilling fluids have been found which possess the characteristics of dielectric breakdown and become more conductive upon application of an electrical potential gradient of practical magnitude. Drilling fluids which display this property and which are therefore useful in the operation of this invention are those oil base drilling fluids which, in addition to mineral oils and/or distillates thereof, weighing agents and the like, contain more than about 1% water such as between about 1 to 20% by weight of water and more than about 1% by weight of a metallic soap such as between about 1 and 20% by weight of metallic soap. Such drilling fluids have resistivities which customarily are greater than 10^4 ohms per centimeter and which are often greater than 10^6 ohms per centimeter.

It has been found that where such drilling fluids are employed in the field, they behave substantially as anhydrous oil base drilling fluids in that the small amount of fluid which is lost to the formation does not induce water blocking, swelling of clays or any of the other difficulties

generally associated with aqueous drilling fluids. Furthermore, it has been found that where the water content is considerably higher, such as 50%, the fluid loss is of such a nature that it does impair the formation character.

In one modification of the invention two electrode plates, suitably positioned at different levels in the well bore, are connected to a source of alternating current whereby an electric field is established between the electrode plates. The equipotential lines passing between the two plates are distorted by the earth formation surrounding the bore hole as a result of the conductive character of the bore hole fluid under the electrical stress.

Two probing electrodes are placed in the electric field between the electrode plates and in fixed spatial relationship with respect to each other and to the electrode plates, and when the resulting assembly is moved coaxially within the bore hole the variation of the potential difference between the two probing electrodes is a measure of the electrical character of the formation surrounding the well bore. The probing electrodes are preferably placed as close to the wall of the well bore as possible in order that the potential difference therebetween is most noticeably affected by the changes of the electrical character of the formation. In the preferred modification the probing electrodes are pressed against and held next to the formation lining the well bore by a suitable spring mechanism.

The preferred modification of the invention includes the use of two probing electrodes disposed between two electrode plates wherein the probing electrodes are employed to measure potential differences. However, in another modification of the invention two electrode plates may be employed without the use of probing electrodes. In the latter modification the electrode plates in fixed spatial relation to each other are moved coaxially through the bore hole and the changing power load required to maintain a particular potential difference between the electrode plates is then a measure of the changing electrical character of the surrounding formation.

In another modification of the invention an electrical gradient is established between two electrode plates. When an electrode is placed in the resulting electrical field it establishes a good electrical connection with the surrounding formation. The electrode for establishing the electrical connection is preferably pressed or held against the surrounding formation such as by suitable spring mechanism. One or several such electrically contacting electrodes, each suitably disposed in an electric field between electrode plates, may be used to carry out any of the conventional electric logging operations such as the self-potential method. In such a case the contacting electrode in the electric field merely provides electrical connection with the earth formation through the interposed oil saturated layer which has undergone dielectric breakdown.

In the accompanying drawing, Figure 1 shows the effect of dielectric breakdown on the resistivity curves for a series of drilling fluids, each of which contains about 2.5% by weight of a soap and each differing from the others in the varying percentages of water.

Figure 2 illustrates the fact that in the absence of dielectric breakdown in the case of two drilling fluids, neither containing more than a trace of soap, there is no variation of the resis-

tivity of such fluids even though potential gradients as high as 1200 volts per inch be employed either in the presence or absence of dispersed water.

Figure 3 shows the preferred modification of the invention wherein two probing electrodes are mounted between two electrode plates carrying a sufficiently high voltage alternating electrical current to cause the dielectric breakdown of the intervening drilling fluid and wherein the electrical characteristics of the surrounding formation are determined by the potential difference between the two probing electrodes.

Figure 4 shows another modification of the invention wherein a first electrode probe disposed between a first pair of electrode plates is employed to establish electrical connection with the surrounding formation at a first point and a second electrode probe disposed between a second pair of electrode plates is employed to establish electrical connection with the surrounding formation at a second point.

It has been found that certain oil base drilling fluids, namely those containing significant percentages of both water and a metallic soap, exhibit a property which herein is termed "dielectric breakdown." When such drilling fluids are subjected to a sufficiently high alternating voltage gradient, they cease to be weak dielectrics and become electrical conductors. In the absence of the dielectric breakdown the fluid exhibits a high resistivity, but when a characteristic voltage is exceeded for the particular fluid, a sharp reduction of the resistivity, often 10 to 100 fold or more, occurs after a short period of application. This invention employs this principle to establish electrical contact between one or more contacting electrodes and the surrounding earth formation in those cases where a film or layer of a normally non-conducting drilling fluid is interposed therebetween. Where the drilling fluid film or layer is of the aforementioned type, the electrical contact can be established by subjecting the interposing drilling fluid to an electrical potential gradient of the proper magnitude whereby the drilling fluid is rendered electrically conducting.

Drilling fluids which may be employed in this invention are those in which a mineral oil is employed as the continuous dispersed phase and amounts to at least about 40% by weight and preferably at least about 60% by weight of the fluid. Such drilling fluids may be either of the oil base type or of the emulsion type and may contain small amounts of certain additives such as lime, bentonite, barytes, starch and the like. In order that the drilling fluid to be operable in this invention it must contain both water and a metallic soap such as between about 1 and 20% by weight of water and preferably between 7 and 17% by weight of water and between about 1 and 20% by weight of a metallic soap and preferably between about 2 and 8% by weight of a metallic soap. The metallic soap of the drilling fluids employed in this invention is preferably an ionizable soap such as an alkali or alkali metal soap derived from higher molecular weight carboxylic or sulfonic acids such as those acids which contain between about 2 and 35 carbon atoms per molecule and preferably between about 10 and 25 carbon atoms per molecule. Among the acids which may be employed as their metallic soaps are various naphthenic acids, rosin acids, modified rosin acids obtained by heat treatment of rosin acids with or without the use of catalysts, such as by heat-

ing at 250°-350° C. until the specific rotation is increased from a negative value to +5 to +15, fatty acids such as stearic acid, and olefinic acids such as oleic acid and the like. Sulfonic acids which are suitable for use in this invention may be conveniently prepared by the sulfonation of petroleum stocks with sulfuric acid, fuming sulfuric acid, chloro-sulfonic acid and the like. In the sulfonation of lube oil stock to prepare a white oil, the sludge is separated and the oil is then extracted with sodium hydroxide whereupon the sodium soap of the sulfonic acid is obtained, which is suitable for use in this invention.

Referring now more particularly to Figure 1, this figure shows the effect of variations of the percentage of water in a drilling fluid on resistivity changes caused by the dielectric breakdown of the fluid. A drilling fluid stock was prepared by intimately mixing together the following ingredients wherein the metallic soap was the potassium soap derived from a heat-modified abietic acid.

Table I

Ingredient:	Percentage by weight	25
Potassium soap	2.5	
Bentonite	1.25	
Lime	0.75	
Petroleum distillate (400-800° F. boiling range)	10.0	30
Light fuel oil	85.5	
Total	100.00	

The modified abietic acid was prepared by heating abietic acid at 280-320° C. for about 4 hours. The foregoing stock was then mixed with sufficient water to form a series of mixtures containing 0%, 2%, 7%, 12% and 17% of water respectively.

The dielectric breakdown of each of the fluid mixtures was measured in the following manner. Two $\frac{1}{8}$ inch platinized steel rods about 2 inches in length were immersed in the fluid mixture and maintained in parallel relationship about $\frac{1}{8}$ of an inch apart. A variable source of 60 cycle alternating voltage connected to the two rods was used to establish potential gradients in excess of 250 volts per inch in the fluid mixture between the rods. In each case the instantaneous resistivity of the particular fluid was calculated from the instantaneous measurements of current flow and the voltage.

Figure 1 shows that all of the fluids containing water in addition to the metallic soap show a characteristic decline in the resistivity with time when the potential gradient is 250 volts per inch, with each resistivity ultimately arriving at a minimum which is progressively lower for the higher percentages of water. In the absence of water the fluid exhibits no decrease in resistivity even under a potential gradient of 250 volts per inch.

When the same series of measurements is repeated using potential gradient of only 160 volts per inch between the rods, a similar decrease of resistivity with increasing exposure time is noted in all cases with the singular exception of the sample containing no water. However, when the measurements are repeated using a potential gradient of only 5 volts per inch between the rods, all of the fluids show a constant high resistivity which does not decrease with increasing time of application of voltage.

Analogous results are obtained when the metallic soap is the sodium soap of a mahogany

acid obtained in the manufacture of white oil. In such a case the lube oil stock is sulfonated with fuming sulfuric acid and the sludge is separated therefrom. The acid containing oil is then neutralized with sodium hydroxide whereupon the soaps are obtained. Such soaps may be employed directly without separation from the residual oil if desired.

When potassium oleate is employed as the soap, a similar result is also obtained. Other alkali and alkali metal soaps of sulfonic and carboxylic acids having between 2 and 35 carbon atoms per molecule behave similarly.

Referring now more particularly to Figure 2, this figure illustrates the absence of dielectric breakdown in oil base drilling fluids which are free of, or substantially lacking in, metallic soaps. A first sample of drilling fluid containing about 0.8% by weight of water was prepared by mixing the following ingredients.

Table II

Ingredients:	Percentage by weight
Asphalt	15
Petroleum distillate (400-800° F. boiling range)	76
Water	0.8
Lime	4
Calcium carbonate (weighting agent)	4.2
Total	100.0

A second sample was prepared by mixing an aliquot of the first sample with sufficient water to form an intimate mixture containing about 10% by weight of water. While no metallic soap was added directly to either of the two samples, nonetheless the natural acids normally present in the asphalt and petroleum distillate were sufficient to react with the lime and form about 0.3% by weight of calcium soaps.

The results obtained by repeating the resistivity measurements described hereinbefore, wherein the two preceding samples were measured at potential gradients up to 1200 volts per inch, are shown in Figure 2. There was no change in resistivity with time or with magnitude of potential gradient, that is, no breakdown voltages were observed.

Referring now more particularly to Figure 3, bore hole 11 has been completed through various earth formations 12 with the use of an oil base drilling fluid containing both water and a metallic soap of the type described hereinbefore. Bore hole 11 remains filled with a drilling fluid 13 and a part of the fluid has penetrated portions of the wall of the bore hole thereby electrically insulating such portions of the bore hole wall. At the earth surface pulley 40 supports cable 41, the upper end of which is wound on winding drum 42. Winding drum 42 is fitted with depth of instrument indicating means not shown. Winding drum 42 is also fitted with suitable contactors 43 which may take the form of slip rings. Leads 44 and 45 connect alternating current generator 46 to contactors 43, which in turn are connected to power leads 47 and 48 carried within cable 41. Cable 41 runs downwardly from the earth surface through bore hole 11 and supports instrument housing 16 which comprises a sealed container housing a high voltage step-up transformer 17 and alternating potential recording means 18. The lower portion of sealed instrument housing 16 is fitted with electrode plate 19 to which is attached a hollow shaft 20 which in turn supports lower electrode plate 21 parallel to and at a fixed

distance from the first electrode plate 19. Non-conducting flexible supporting members 22 and 23 are suitably mounted in the inner space between parallel electrode plates 19 and 21. Each non-conducting supporting member mounts a pair of probing electrodes or probes, probes 24 and 25 being mounted on member 22 and probes 26 and 27 being mounted on member 23 respectively. Probes 24 and 25 bear the same vertical distance relationship to each other and to parallel electrode plates 19 and 21 respectively as do probes 26 and 27 respectively. Upper probes 24 and 26 are interconnected by electrical lead 28 while lower probes 25 and 27 respectively are interconnected by lead 29. Leads 28 and 29 pass into hollow shaft 20 through suitable insulators and thence upwardly through shaft 20 to alternating potential recording means 18.

The primary of transformer 17 is connected to leads 47 and 48 which are in turn connected to alternating current generator 46 in the manner described hereinbefore. The secondary of transformer 17 is connected by electrical lead 30 to electrode plate 19 and by lead 31, passing through hollow shaft 20, to lower electrode plate 21.

In the operation of the equipment the instrument is lowered in the bore hole by means of supporting power supply cable 41 to the approximate level of the formation to be logged. An alternating current is transmitted from alternating current generator 46 by connecting leads and commutators to transformer 17 which steps up the voltage as desired. The output of transformer 17 is supplied to the two electrode plates 19 and 21 respectively whereby an electric field is set up in the oil base drilling fluid disposed between and around the electrode plates. As a result of high electrical stress the surrounding drilling fluid undergoes a dielectric breakdown and becomes electrically conductive. The lines of electrical force between the two electrode plates 19 and 21 extend outwardly through the conducting oil and the oil film into the formation. Accordingly, the conductivity of the surrounding formation affects the electric field set up by the electrode plates. As the apparatus is raised and lowered in the bore hole, the changing electrical character of the formation beyond the permeated oil layer alters the electrical field between the electrode plates, and thereby changes the voltage gradient existing between upper probes 24 and 26 and lower probes 25 and 27 respectively. The changing electrical potential between the two pairs of probes as the apparatus is moved through the length of the bore hole is transmitted through connecting leads 28 and 29 to alternating voltage potential recording means 18. Voltage recording means 18 is any convenient type of instrument for measuring and recording alternating voltage differences. One convenient form of such instrument is a voltmeter of the conventional type wherein a light is caused to shine on a mirror attached to the pointer of the voltmeter. The swing of the voltmeter causes the reflected light beam to swing back and forth across the moving strip of photographic film whereby voltage variations produce corresponding fluctuations of the position of the reflected light beam on the photographic film. Development of the photographic film gives a record of the measurements. When the measurements are correlated with the depth, there is obtained an electrical record of the character of the formation surrounding the bore hole in any location.

For the convenience of stepping up the volt-

age the frequency of the electrical current supplied from alternating current generator 46 is preferably between about 25 and 400 cycles per second. The use of frequencies of less than about 25 cycles per second often leads to adverse polarization effects. The voltage produced by alternating current generator 46 is any suitable voltage which can be transmitted through cable 41 without severe losses and insulating difficulties. For example, a suitable voltage output would be in the range between about 40 and 1000 volts. Transformer 17 is adapted to step up the supply voltage from alternating current generator 46 to the required voltage to establish a dielectric breakdown of the oil base mud between electrode plates 19 and 21 respectively. The use of transformer 17 simplifies somewhat the transmission of the electrical energy down the bore hole by eliminating the necessity of energy transmission at higher voltages with attendant insulation problems.

It is generally necessary to establish a voltage gradient of about 100 volts per inch and preferably about 200 volts or more per inch in the oil base drilling fluids of the invention in order to effect their dielectric breakdown. The physical separation between the opposing exposed faces of the electrode plates 19 and 21 respectively is normally between about 1 and 20 inches and preferably between about 1 and 8 inches. The output of the transformer 17 is preferably in the range of 1000 to 3000 volts.

While the foregoing description of the invention has to some extent been limited to those frequencies which are conveniently stepped up by the transformer, it is apparent that higher or lower frequencies may be employed if suitable means for their generation, such as an electric oscillator and amplifier, is included in the apparatus. When such generating means are employed, they may be located in the bore hole and near the electrode plates whereby the necessity of extensive insulating means for the transmission of high voltage electric currents is eliminated.

In the foregoing description of this invention two upper probes, 24 and 26 respectively, and two lower probes, 25 and 27 respectively have been employed. Upper probes 24 and 26 are electrically connected in parallel and lower probes 25 and 27 similarly are electrically connected in parallel. It is apparent that the invention is not limited to the use of only two upper and two lower probes. In some cases only a single upper and a single lower probe may be employed, and in other cases multiple wires or even wire mesh may be used to make the resulting log more nearly representative of the entire formation surrounding the unit.

Although the foregoing description of this invention has been directed primarily to the continuous application of electrical current to the electrode plates, short bursts of electrical energy may be employed for certain specific cases. Thus, after the minimum resistivity is obtained by exposure to the proper potential gradient for the required length of time, e. g. 25 to 500 seconds, the electrical current is applied by a suitable timing device to the electrode plates for a short period of time, such as for example 10 to 500 milliseconds. The activation voltage is thereupon disconnected for a short period of time, such as 10 to 500 milliseconds, during which time electrical measurements of the surrounding formation are made. Follow-

ing the measuring period the next activation period is commenced with the sequence of activating and measuring being repeated numerous times as desired.

With certain drilling fluids of this invention it is possible to establish the breakdown of the oil with a relatively high voltage and thereafter maintain the breakdown by the continuous application of a lesser voltage provided a characteristic minimum is maintained. When the voltage falls below the minimum characteristic for the particular fluid, the current flow drops rapidly to a very low value as the resistivity increases.

In another method for electrically logging a formation, the equipment shown in Figure 3 is operated by simply supplying an alternating current from transformer 17 to electrode plates 19 and 21 and measuring the changes in power consumption as the apparatus is moved through the bore hole. In such a case the previously described probing electrodes, 24 and 26, and 25 and 27 may be utilized simultaneously as described hereinbefore or they may be dispensed with entirely and a single log of the power consumption may be obtained.

Referring now more particularly to Figure 4, bore hole 51 has been completed through various earth formations 52, the drilling operation having been carried out with an oil base drilling fluid containing both a metallic soap and water. Bore hole 51 remains partially filled with such oil base drilling fluid 53. Sealed housing 54 is suspended within bore hole 51 below the surface of drilling fluid 53 by means of supporting cable 55 which also carries insulated power leads 57 and 58, respectively. At the earth surface power leads 57 and 58 are electrically connected to a suitable source of alternating electrical current by a suitable means not shown. Sealed housing 54 contains transformer 59 which is equipped with a tapped secondary winding and also a potential measuring and recording means 60.

Attached to the lower end of housing 54 is first upper electrode plate 61. Hollow non-conducting supporting shaft 62 extends downwardly from its point of attachment to electrode plate 61. Lower first electrode plate 63 is supported by supporting shaft 62 a short distance below upper first electrode plate 61 in parallel relationship thereto. Flexible non-conducting supporting members 64 and 65 respectively are suitably mounted between upper and lower first electrode plates 61 and 63 respectively. Each of the two supporting members 64 and 65 respectively mounts probing electrodes 66 and 67 respectively, both electrodes being electrically connected in parallel by means of lead 68. Some distance below the lower first electrode plate 63 an upper second electrode plate 69 and a lower second electrode plate 70 are mounted on supporting shaft 62 in parallel relationship to each other and to the upper and lower first electrode plates 61 and 63 respectively. In a manner similar to that described hereinbefore for upper and lower first electrodes plates 61 and 63 respectively, upper and lower second electrode plates 69 and 70 furnish support for two flexible non-conducting supporting members 71 and 72 respectively. The two supporting members 71 and 72 in turn mount probing electrodes 73 and 74 respectively, which probing electrodes are adapted to press against a part of the formation in between the two second electrode plates. Probing electrodes 73 and 74 are electrically connected by lead 75.

The first outer terminal of the secondary of transformer 59 is connected by electrical lead 76 to upper first electrode plate 61. The middle tapped output of transformer 59 is connected by lead 77 to lower first electrode plate 63 and to lower second electrode plate 70. The second outer terminal of transformer 59 is connected by means of lead 78 to the upper second electrode plate 69.

10 Potential measuring and recording instrument 60, which is preferably of the photographic type described hereinbefore, is connected through lead 68 to probing electrodes 66 and 67 respectively, and is connected through lead 75 to probing electrodes 73 and 74 respectively.

In the operation of the apparatus of Figure 4 an alternating electrical current of the type described hereinbefore is supplied through leads 57 and 58 to transformer 59 which suitably steps up the voltage. The voltage difference between the first outer terminal and the middle terminal is employed to establish a potential gradient between the upper and lower first electrode plates 61 and 63 respectively, thereby providing for the dielectric breakdown of the drilling fluid within the resulting first electrical field. The voltage difference between the middle terminal and the second outer terminal is employed to establish a potential gradient between the upper and lower second electrode plates 69 and 70 respectively, thereby providing for the dielectric breakdown of the drilling fluid within the resulting second electric field. The electrical conducting character of the formation permits varying flow of electrical current between the first electrical field and the second electrical field owing to the potential difference between the instantaneous potentials of the two electric fields. The variations of current flow are indicated by the corresponding variations in the potential difference between the first pair of probing electrodes and the second pair of probing electrodes. This latter potential difference is transmitted through leads 68 and 75, respectively, to potential measuring and recording means 60. The recording means preferably operates in the manner described hereinbefore in connection with Figure 3 although other suitable means may be employed. Development of the photographic film gives a measure of the electrical character of the formation surrounding the bore hole between the first and second electrical fields.

Although transformers disposed within the bore hole have been employed to illustrate the principles of this invention, it is apparent that the use of such transformers is not a requirement of the invention. Thus, a higher voltage source at the earth surface may be employed with suitable provision being made to transmit such voltage down the bore hole to the electrode plates.

60 It is apparent that the invention is not limited to the use of only two probe electrodes connected in parallel and mounted in between each pair of electrode plates. One or several such probing electrodes may be employed.

65 In the foregoing description of the particular modification of the invention, the high voltage leads 76 and 77 to electrode plates 61 and 63 respectively may be reversed with or without the simultaneous reversal of the high voltage leads 77 and 78 to electrode plates 69 and 70 respectively, or the latter voltage leads 77 and 78 alone may be reversed.

70 It is apparent that in the general application of the invention one or more electric fields are set

up between one or more pairs of electrode plates, which pairs of electrode plates may be separated from other pairs of electrode plates by any desired distance, which plates may or may not be planar and which plates are in electrical contact with the surrounding oil base drilling fluid. The probing electrodes are disposed within each of the electric fields and are employed to establish electrical contact between voltage or current measuring apparatus and the earth formation surrounding the electric field or alternatively to provide an electric connection for impressing a voltage upon the formation. By using this general method various types of logs may be made in conventional manner, e. g., by the self-potential method wherein a first contact electrode is moved up and down the bore hole between two electrode plates and the second contact electrode is embedded in and located in the earth surface.

In another modification of the invention the earth formation itself may be made to serve as one of the electrode plates. Two electrodes are placed in the bore hole and are separated by a known distance. A center tapped source of alternating current is employed and the one outer terminal is electrically connected to the one electrode while the other outer terminal is connected to the other electrode. The center tap is grounded such as at the earth surface. Under these conditions the earth formation is always at a different potential than either of the two electrodes. When this potential difference is sufficient to cause a dielectric breakdown of the oil base mud between electrode and the surrounding formation, electric current begins to flow through the formation between the two electrodes. The magnitude of the current is dependent upon the electrical character of the surrounding formation and is most easily determined from the power consumed in maintaining the constant potential between the electrodes. For such purpose a sufficiently high voltage is employed to cause the dielectric breakdown of the oil between the formation and the electrodes.

In the general application of this invention there is a time delay between the application of the activating voltage and the dielectric breakdown. Once the breakdown has been established, such as after about 25 to 500 seconds of application of the breakdown voltage, only short bursts of activating energy are required to sustain the lowered resistivity of the drilling fluid. Thus, after the initial activating, short bursts of electrical energy of about 10 to 500 milliseconds duration may be employed after short periods of measurement taking, which may be of about 10 to 500 milliseconds duration.

It is apparent that many modifications of this invention may be made by those skilled in the art without departing from the spirit and scope of the following claims.

I claim:

1. A method for electrically contacting a portion of a bore hole wherein said portion of said bore hole has been drilled with a drilling fluid which comprises at least about 60% by weight of mineral oils and distillates thereof, between about 1% and about 20% by weight of water, and between about 1% and about 20% by weight of a metallic soap selected from the class consisting of alkali and alkali metal soaps of carboxylic and sulfonic acids having between about 2 and 35 carbon atoms per molecule, which method of contacting comprises establishing a voltage gradient zone throughout a vertical portion of said

bore hole, said voltage gradient of said voltage gradient zone being at least about 100 volts per inch, thereby effecting the dielectric breakdown of said drilling fluid in said zone, and passing electrical energy from an electrode disposed in said zone to the section of the wall of said well bore surrounding said zone and thereby establishing electrical contact therewith.

2. A method of electrically logging a portion of a bore hole wherein said portion of said bore hole has been drilled with a drilling fluid which comprises at least about 60% by weight of mineral oils and distillates thereof, between about 1% and about 20% by weight of water, and between about 1% and about 20% by weight of a metallic soap selected from the class consisting of alkali and alkali metal soaps of carboxylic and sulfonic acids having between about 2 and 35 carbon atoms per molecule, which method of logging comprises establishing a voltage gradient zone throughout a vertical portion of said bore hole, said voltage gradient of said voltage gradient zone being at least about 100 volts per inch, thereby effecting the dielectric breakdown of said drilling fluid in said zone, moving said voltage gradient zone vertically within said bore hole and measuring the voltage difference between a point within said zone and a portion of said oil bearing formation.

3. A method of electrically logging a portion of a bore hole wherein said portion of said bore hole has been drilled with a drilling fluid which comprises at least about 60% by weight of mineral oils and distillates thereof, between about 1% and about 20% by weight of water, and between about 1% and about 20% by weight of a metallic soap selected from the class consisting of alkali and alkali metal soaps of carboxylic and sulfonic acids having between about 2 and 35 carbon atoms per molecule, which method of logging comprises establishing a voltage gradient zone throughout a vertical portion of said bore hole, said voltage gradient of said voltage gradient zone being at least about 100 volts per inch, thereby effecting the dielectric breakdown of said drilling fluid in said zone, moving said zone vertically within said bore hole and continuously measuring the electrical energy required to sustain said voltage gradient.

4. The method of electrically contacting a well bore wherein said well bore has been drilled with a drilling fluid which comprises at least about 60% by weight of mineral oils and distillates thereof, between about 7 and 17% by weight of water, and between about 2 and 8% by weight of a metallic soap selected from the class consisting of alkali and alkali metal soaps of carboxylic and sulfonic acids having between about 2 and 35 carbon atoms per molecule, which method of contacting comprises introducing two spaced electrode plates below the surface of said oil base drilling fluid in said well bore, supplying an alternating current to said two electrode plates having a frequency between about 25 and 400 cycles per second and thereby establishing a voltage gradient in the said drilling fluid between said two electrode plates of at least about 100 volts per inch, and passing electrical energy between a probing electrode, maintained in fixed spatial relationship to said two electrode plates, and the wall of the well bore laterally surrounding said probing electrode and thereby establishing electrical contact therewith.

5. The method of electrically contacting a well bore wherein said well bore has been drilled with a drilling fluid which comprises at least about

60% by weight of mineral oils and distillates thereof, between about 7 and 17% by weight of water, and between about 2 and 8% by weight of a metallic soap selected from the class consisting of alkali and alkali metal soaps of carboxylic and sulfonic acids having between about 2 and 35 carbon atoms per molecule, which method comprises introducing two spaced electrode plates below the surface of said oil base drilling fluid in said well bore, supplying an alternating current to said two electrode plates having a frequency between about 25 and 400 cycles per second and thereby establishing a voltage gradient in the said drilling fluid between said two electrode plates of at least about 100 volts per inch, continuing said supplying of alternating current for a period of between about 25 seconds and 500 seconds, discontinuing said supplying of said alternating current during a measuring period of between about 10 and 500 milliseconds, continuing said supplying of said alternating current during an activation period of between about 10 and 500 milliseconds, and repeating said sequence of measuring periods and activation periods, and passing an electrical current between a probing electrode maintained in fixed spatial relationship to said two electrode plates and the wall of the well bore laterally surrounding said probing electrode during a measuring period, and thereby establishing electrical contact therewith.

6. The method of electrically logging a well bore wherein said well bore has been drilled with a drilling fluid which comprises at least about 60% by weight of mineral oils and distillates thereof, between about 7 and 17% by weight of water, and between about 2 and 8% by weight of a metallic soap selected from the class consisting of alkali and alkali metal soaps of carboxylic and sulfonic acids having between about 2 and 35 carbon atoms per molecule, which method comprises introducing two spaced electrode plates below the surface of said oil base drilling fluid in said bore hole, establishing an alternating current voltage gradient of at least about 100 volts per inch and of a frequency between about 25 and 400 cycles per second in said drilling fluid between said two electrode plates, thereby effecting the dielectric breakdown of said oil base drilling fluid near and between said two electrode plates, and measuring the potential difference between two probing electrodes which are maintained in fixed spatial relationship to said two electrode plates and to each other.

7. The method of electrically logging a well bore wherein said well bore has been drilled with a drilling fluid which comprises at least about 60% by weight of mineral oils and distillates thereof, between about 7 and 17% by weight of water, and between about 2 and 8% by weight of a metallic soap selected from the class consisting of alkali and alkali metal soaps of carboxylic and sulfonic acids having between about 2 and 35 carbon atoms per molecule, which method comprises introducing a series of four electrode plates into said bore hole below the surface of said oil base drilling fluid, said series comprising a first electrode plate, a second electrode plate disposed below said first electrode plate, a third electrode plate disposed below said second electrode plate and a fourth electrode plate disposed below said third electrode plate, supplying a first alternating current voltage to said first and said second electrode plates and establishing a voltage gradient of at least about 100 volts per inch and causing the dielectric breakdown of the portion of said

oil base drilling fluid disposed near and therebetween, supplying a second alternating current voltage to said third and said fourth electrode plates and thereby establishing a voltage gradient of at least 100 volts per inch and causing the dielectric breakdown of the portion of said oil base drilling fluid disposed near and therebetween, and measuring the voltage difference between a first probing electrode maintained in fixed spatial relationship to said first electrode plate and said second electrode plate, and a second probing electrode maintained in fixed spatial relationship to said third electrode plate and said fourth electrode plate.

8. An apparatus for electrically logging a well bore which comprises at least about 60% by weight of mineral oils and distillates thereof, between about 1% and about 20% by weight of water, and between about 1% and about 20% by weight of a metallic soap selected from the class consisting of alkali and alkali metal soaps of carboxylic and sulfonic acids having between about 2 and 35 carbon atoms per molecule, a unit adapted for coaxial movement within a well bore which comprises an upper electrode plate, a lower electrode plate, a probing electrode disposed therebetween, an alternating current generating means connected to said upper and said lower electrode plates, said alternating current generating means having a generating capacity greater than about 100 volts per inch of separation distance between said upper electrode plate and said lower electrode plate, and electrical measuring means connected to said probing electrode for determining the difference of potential between said probing electrode and a portion of the oil bearing formation surrounding said well bore.

9. An apparatus for electrically logging a well bore which comprises at least about 60% by weight of mineral oils and distillates thereof, between about 1% and about 20% by weight of water, and between about 1% and about 20% by weight of a metallic soap selected from the class consisting of alkali and alkali metal soaps of carboxylic and sulfonic acids having between about 2 and 35 carbon atoms per molecule, a unit adapted for coaxial movement within a well bore which comprises an upper electrode plate, a lower electrode plate, two probing electrodes disposed between and maintained in fixed vertical relationship to said upper electrode plate and said lower electrode plate, an alternating current generating means connected to said lower electrode plate and said upper electrode plate, the generating capacity of said alternating current generating means being greater than 100 volts per inch of separation distance between said lower electrode plate and said upper electrode plate, and an electrical measuring means connected to said two probing electrodes for measuring the potential difference therebetween.

10. An apparatus for electrically logging a well bore which comprises at least about 60% by weight of mineral oils and distillates thereof, between about 1% and about 20% by weight of water, and between about 1% and about 20% by weight of a metallic soap selected from the class consisting of alkali and alkali metal soaps of carboxylic and sulfonic acids having between about 2 and 35 carbon atoms per molecule, a unit adapted for coaxial movement within a well bore which comprises an upper electrode plate, a lower electrode plate, a series of four electrode plates which comprises a first electrode plate, a

second electrode plate disposed below said first electrode plate, a third electrode plate disposed below said second electrode plate and a fourth electrode plate disposed below said third electrode plate, a first probing electrode disposed between said first and said second electrode plates, a second probing electrode disposed between said third and said fourth electrode plates, a first alternating current generating means connected to said first and said second electrode plates, the generating capacity of said first alternating current generating means being greater than 100 volts per inch of separation distance between said first and said second electrode plates, a second alternating current generating means connected to said third and said fourth electrode plates, the generating capacity of said second alternating current generating means being greater than 100 volts per inch of separation distance between said third and said fourth electrode plates, and means for determining the potential difference between said first probing electrode and said second probing electrode.
